G. H. ELWELL,
DOOR LATCH.
APPLICATION FILED SEPT. 27, 1915.

Patented Oct. 16, 1917.

FIG. 1.

Fig. 2.

FIG. 3.

FIG. 5.

WITNESSES:

George Henry Elwell INVENTOR.

UNITED STATES PATENT OFFICE.

GEORGE HENRY ELWELL, OF BOSTON, MASSACHUSETTS.

DOOR-LATCH.

1,243,596.

Specification of Letters Patent. Patented Oct. 16, 1917.

Application filed September 27, 1915. Serial No. 52,870.

To all whom it may concern:

Be it known that I, GEORGE HENRY ELWELL, of Boston, in the county of Suffolk, Commonwealth of Massachusetts, and 5 United States of America, have invented an Improvement in Door-Latches, of which the following description, in connection with the accompanying drawing, is a specification, like characters on the drawing representing characters on the drawing repre-

10 senting like parts.

My invention relates to improvements in door latches and more particularly to that class of latches employing a bolt with a hook-shaped head for interlocking engagement with the striker-plate.

The object of my invention is to provide a latch bolt fully adapted to the elasticity of motor car bodies and like uses.

With this and other objects in view, as 20 will more fully hereinafter appear, the invention consists in certain novel features of construction and arrangement of parts hereinafter described, illustrated in the accompanying drawing and particularly 25 pointed out wherein patentable novelty is claimed for certain features of the device, it being understood that within the scope of what hereinafter thus is claimed various changes in form, proportion, size and minor 30 details of the construction may be made without departing from the spirit or modifying any of the advantages of the invention.

The following is a description of an embodiment of my invention, reference being had to the accompanying drawings:

In the accompanying drawings, Figure 1 is an upright view of the mechanism of the device.

40 Fig. 2 is a top view of the device.

Fig. 3 is a detail cross section view of incasement, lever and bolt, at dotted line *a—a* in Fig. 2.

Fig. 4 is a detail cross section view of incasement and bolt at dotted line *b—b* in 45 Fig. 2.

Fig. 5 is a detail in dotted lines showing bolt sections in super position with slightly operated lever.

50 Referring more particularly to the drawings,

A supporting plate or incasement 1 is provided with a face 2 having a perforation 3, said incasement 1 being also provided 55 with a back 4 having a perforation 5, said face 2 and back 4 with their perforations 3

and 5 providing guiding bearings for a sliding bolt 6, as shown in Figs. 1 and 2. The bolt 6 is provided with a beveled head 7 for engaging a striker-plate 33 and is also 60 provided with a laterally movable section 8 pivoted at 31 and having a hook 9 provided with a beveled face and normally maintained in a projected position by means of a spring 10 mounted on an assembling 65 pin 32, as shown in Fig. 2. The incasement 1 is also provided with two movable conveyers 18 and 20. Conveyer 18 is yieldingly maintained in its normal rearward position, as shown, by means of springs 19, 70 so as to travel in the space 15 under said bolt 6 when in engagement with and pushed forward by arms 28 secured to bolt 6 as shown in Fig. 1. Conveyer 20 is maintained in its normal forward position by 75 means of a spring 22 so as to travel in the space 17 under said bolt 6 when in engagement with and pushed rearwardly by bolt 6. It has a projection 36 lying between arms 11 of said bolt 6 adapted to be engaged by the 80 rear of member 8. The incasement 1 is provided with a slot 21 regulating the travel of the parts connected to pin 35, which assembles said spring 22 with said conveyer 20 as shown in Fig. 1. A lever 12 is provided 85 with a bent attaching end 13 attached to incasement 1 by means of a rivet 14 as shown in Fig. 1 permitting the operation of said lever 12 in space 16 under said bolt 6 as shown in Fig. 2. Said lever 12 is normally maintained in an upright position by 90 means of an arm of spring-pressed conveyer 20 and check 23 with which said incasement 1 is provided as shown in Fig. 1. The lever 12 is provided with a transverse recess 27 95 for travel of bolt 6, and said recess 27 is provided with shoulder 26 over which recess 25 in bolt 6 travels when lever 12 is in an upright position as shown in Figs. 3 and 4. Said shoulder 26 upon operation of lever 100 12 moves downwardly and engages a vertically sloping bevel 24 of section 8 of bolt 6 raising said section 8 on pivot pin 31 away from the incasement 1, and thus retiring said hook 9 within the bevel head 7 of bolt 6. 105 A bearing above the shoulder 29 formed by recess 27 in lever 12 is intended for engagement with a shoulder 30 with which bolt 6 is provided when the lever 12 is slightly tilted as shown in Fig. 5.

In operation when the latch is in an interlocking engagement with the striker-plate

33 any strain tending to separate the striker-plate from the latch incasement extends the projection of said bolt head according to said strain and the arms 28 of bolt 6 advance 5 the conveyer 18 against the exertion of the springs 19, said conveyer returning to its normal rearward position under the action of springs 19 when tension on bolt 6 is relaxed. In the extended advance 10 movement of said bolt head bolt 6 travels freely over lever 12 and conveyer 20 without operating them. When the bolt head is retired by means of engagement of its beveled face with the striker-plate, the retarding movement of said bolt travels freely 15 over the conveyer 18 and lever 12 without engaging or operating them. When the bolt head is retired by means of lever 12, the shoulder 26 in its downward movement 20 operates the hook section 8, as aforesaid, and the shoulder 29 of lever 12 engaging the shoulder 30 of bolt 6 forces the bolt 6 backwardly. The bolt 6 is thus operated by a lever in the usual way but when in 25 holding engagement with the striker-plate is hooked thereto by the hook 9 whose nose projects over an inner surface on the striker-plate, and is drawn forward by any separation due to rocking of the frame of 30 the car, returning to normal position when the door and its jamb return to normal position. The rigid end of the body of the bolt 6 projects beyond the inner surface of the nose of the hook so as to engage the 35 side of the opening in the striker-plate, and preferably extends so as to terminate in substantially the same transverse plane as the end of the hook.

As will be evident to those skilled in the 40 art, my invention permits of various modifications without departing from the spirit thereof or the scope of the appended claims.

What I claim is:

1. A door-holding means comprising a 45 striker-plate and a latch mechanism having a bolt provided with a hook normally yieldingly held in an intermediate longitudinal position, from which it can be moved in either direction, and in a laterally projecting position with its nose extending over a rearward face on said striker-plate, and manual means for retracting said hook laterally and said bolt longitudinally from 50 said striker-plate.

55 2. A door-holding means comprising a striker-plate and a latch mechanism having a bolt provided with a rigid forward end and a laterally movable hook normally yieldingly held in an intermediate longitudinal position, from which it can be moved in either direction, and in a laterally projecting position with its nose extending over a rearward face on said striker-plate, said rigid forward end extending beyond 60 the inner surface of said hook and manual

means for retracting said hook laterally and said bolt longitudinally from said striker-plate.

3. A door-holding means comprising a striker-plate and a latch mechanism having a bolt provided with a rigid forward end and a laterally movable hook normally yieldingly held in an intermediate longitudinal position, from which it can be moved in either direction, and in a laterally projecting position with its nose extending over a rearward face on said striker-plate, said rigid forward end and the end of said hook terminating in substantially the same transverse plane, and manual means for retracting said hook laterally and said bolt longitudinally from said striker-plate. 70 75 80

4. A door-holding means comprising a striker-plate and a latch mechanism having a bolt provided with a hook normally yieldingly held in an intermediate longitudinal position, from which it can be moved in either direction, and in a laterally projecting position with its nose extending over a rearward face on said striker-plate and manual means for retracting said hook laterally and said bolt longitudinally from said striker-plate, said bolt being provided with a beveled end surface adapted to engage and be retracted by said striker-plate 90 as a door bearing said lock is swung to closed position. 95 100

5. The combination of a supporting plate, a bolt mounted thereon and consisting of a movable member having a guided body portion and a hook member movably connected to said movable member and normally in laterally projected position, spring means permitting said movable member to be moved in either forward or rearward direction from a normal intermediate position and adapted to return it to said intermediate position, and a striker-plate with the inner surface of which said hook is adapted to engage, and manual means for retracting 105 said hook laterally and said bolt longitudinally. 110

6. The combination of a supporting plate, a bolt mounted thereon and consisting of a movable member having a guided body portion and a hook member movably connected to said movable member and normally in laterally projected position, spring means permitting said movable member to be moved in either forward or rearward direction from a normal intermediate position, and a striker-plate with the inner surface of which said hook is adapted to engage, and manual means for retracting said hook laterally and said bolt longitudinally, one of 115 said members having a beveled face upon its end adapted to engage and be forced longitudinally inward by said striker-plate as a door bearing said lock is swung to closed position. 120 125 130

7. The combination of a supporting plate, a bolt mounted thereon and consisting of a movable member having a guided body portion and a hook member movably connected to said movable member and normally in laterally projected position, spring means permitting said movable member to be moved in either forward or rearward direction from a normal intermediate position and adapted to return it to said intermediate position, said hook being adapted to engage the inner surface of a striker-plate, and manual means for retracting said hook laterally and said bolt longitudinally, both of said members having beveled faces upon their ends adapted to engage and be forced inward longitudinally by said striker-plate when a door bearing said lock is swung to closed position.

20 8. The combination of a supporting plate, a bolt mounted thereon consisting of a sliding member carrying a hook, means for yieldingly holding said bolt in an intermediate position from which it is free to move 25 in either direction and said hook in a laterally projected position, and manually operative means engaging with said bolt for manually retracting said hook laterally and said bolt longitudinally away from a 30 striker-plate.

9. The combination of a supporting plate, a bolt mounted thereon and consisting of a movable member having a guided body portion and a hook member movably connected 35 to said movable member and normally in laterally projected position, spring means permitting said movable member to be moved in either forward or rearward direction from a normal intermediate position and adapted to return it to said intermediate position, and a striker-plate with the inner 40 surface of which said hook is adapted to engage, and manual means for retracting said hook laterally and said bolt longitudinally, 45 said striker-plate being adapted to abnormally extend said bolt upon the separation of said supporting and said striker-plates by a relative movement parallel to the plane of said supporting plate.

50 10. The combination of a supporting plate, a bolt mounted thereon and consisting of a movable member having a guided body portion and a hook member movably connected to said movable member and normally 55 in laterally projected position, spring means permitting said movable member to be moved in either forward or rearward direction from a normal intermediate position and adapted to return it to said intermediate position, said hook being adapted to engage the inner surface of a striker-plate, and a lever for retracting said hook laterally and said bolt longitudinally, said 60 hook member and lever having one a cam surface sloping in a vertical direction and

the other a laterally projecting surface adapted to engage therewith, one of said surfaces moving in a vertical direction as said lever is actuated.

11. The combination of a supporting plate, a bolt mounted thereon and consisting of a movable member having a guided body portion and a hook member movably connected to said movable member and normally in laterally projected position, spring 70 means permitting said movable member to be moved in either forward or rearward direction from a normal intermediate position, said hook being adapted to engage the inner surface of a striker-plate, and a lever for 75 retracting said hook laterally and said bolt longitudinally, said hook member having an upwardly sloping cam surface and said lever having a laterally projecting face engaging said cam surface and moving downwardly as said lever is moved in retracting direction.

12. A door latch comprising a proper incasement, a latch bolt provided with a beveled head forming a hook, said bolt being 90 slidably mounted within said incasement and being capable of advancing said head through a perforation with which the face of said incasement is provided to and beyond normal latching position, spring means 95 to advance and maintain said bolt in its normal latching position, counteracting spring means to return said bolt to its normal latching position when against the exertion of said counteracting spring means 100 said bolt has been extended by external means beyond said normal latching position, and means to retire said bolt head within said incasement.

13. A door latch-catch comprising a proper 105 incasement, a beveled head latch bolt slidably mounted within said incasement and being capable of advancing said head to and beyond normal latching position through a perforation with which the 110 face of said incasement is provided, a catch member pivoted to and carried by said latch bolt, said catch member normally projecting laterally from the beveled side of said bolt head, spring means exerted to normally 115 maintain said catch member in its projected position, spring means exerted to advance and maintain said latch bolt in its normal latching position, counteracting spring means to return said latch bolt to its normal 120 latching position when, against the exertion of said counteracting spring means, said bolt has been extended, by external means, beyond said normal latching position, and means to retire said catch member 125 and said latch bolt head against their respective spring means within said incasement.

14. A door latch comprising a proper incasement, said incasement being provided 130

with a bolt passage extending through the face of said incasement, bolt advancing spring means mounted within said incasement, means with which said incasement is provided in said bolt passage to arrest the exertion of said spring means, counteracting spring means mounted within said incasement, means with which said incasement is provided in said bolt passage to arrest the exertion of said counteracting spring means, a latch bolt provided with a beveled head forming a hook, said bolt being slidably mounted in said bolt passage of said incasement, shoulders with which said latch bolt is provided lying between and respectively engaging said spring means and said counteracting spring means, and means to retire said bolt within said incasement.

15. A door latch-catch comprising a proper incasement, said incasement being provided with a bolt passage extending through the face of said incasement, bolt advancing spring means mounted within said incasement, means with which said incasement is provided in said bolt passage to arrest the exertion of said spring means, counteracting spring means mounted within said incasement, means with which said incasement is provided in said bolt passage to arrest the exertion of said counteracting spring means, a beveled head latch bolt slidably mounted in said bolt passage of said incasement, shoulders with which said latch bolt is provided lying between and respectively engaging said spring means and said counteracting spring means, a catch member pivoted to and carried by said latch bolt, said catch member normally projecting lat-

erally from the beveled side of said bolt head, spring means exerted to normally maintain said catch member in its projected position, and means to retire said catch member and said latch bolt against their respective spring means within said incasement.

16. In a safety catch for swinging doors, comprising a striker-plate and a latch mechanism, the combination of a base-plate adapted to be secured to a door, a hooked latch mounted thereon so as to be movable longitudinally and about a pivot relatively thereto and provided with a beveled face on its inner side, a striker-plate engaged by said beveled face so as to move said latch about said pivot as said door closes, said striker-plate having a rearwardly facing surface behind which the hook of said hooked latch lies after movement about said pivot when the door is closed, spring means for permitting said hooked latch to be drawn longitudinally outward relatively to said base-plate and said base-plate and striker-plate to be drawn apart when said hook is in engagement with said rearwardly facing surface and tending to restore said parts to normal position and manually actuated means for freeing said hooked latch from holding engagement with said striker-plate so as to permit the opening of the door.

In testimony whereof I have signed my name to this specification.

GEORGE HENRY ELWELL.
